UNITED STATES PATENT OFFICE.

EDWARD C. KAHN, OF MILWAUKEE, WISCONSIN.

METALLIC FENCE-POST.

1,048,414.

Specification of Letters Patent. Patented Dec. 24, 1912.

Application filed August 9, 1911. Serial No. 643,138.

To all whom it may concern:

Be it known that I, EDWARD C. KAHN, a citizen of the United States, residing at Milwaukee, county of Milwaukee, and State of 5 Wisconsin, have invented new and useful Improvements in Metallic Fence-Posts, of which the following is a specification.

My invention relates to improvements in metallic fence posts, and it pertains more 10 especially, among other things—1st, to the construction of the vertical standard of the post, which is U-shaped in cross section, 2nd, to the construction of the anchor, and 3rd, to the device for slidably connecting the an- 15 chor to the standard, whereby the standard may be first driven separately from the anchor, when the anchor is thereafter driven and secured in place upon the standard by a brace and bolt.

20 My invention is further explained by reference to the accompanying drawings, in which—

Figure 1 represents a side view. Fig. 2 is a rear view, and Fig. 3 is a transverse sec- 25 tion drawn on line $x-x$ of Fig. 2.

Like parts are represented by the same reference numerals throughout the several views.

1 is a standard, which is formed of ordi- 30 nary commercial iron, U shape in cross section, when it is cut into the required lengths and provided with one or more apertures 2, for the reception of the brace retaining bolt 3. The lower end of the standard is then 35 preferably flattened and pointed as shown at 4, to facilitate driving.

The anchor comprises two plates 5 and 6. The plate 5, preferably converges down- 40 wardly from its upper edge 7 to its lower edge 8. A short horizontal slit 9 is then formed, when the portions of the plate above and below the slit are curved toward the right and left in opposite directions, so as to form the curved fastening flanges 10 45 and 11, when said flanges 10 and 11 are re- spectively secured to the front rectangular plate 6 by bolts 13, 13. The flanges 10 and 11 are curved to conform to and nicely fit the exterior surface of the standard 1, as 50 more clearly shown in Fig. 3, while the plate 6, when secured in place by said bolts, is adapted to bear firmly against the respective edges of the U-shaped standard. When 55 said parts are thus secured together, they are adapted to be slidably supported upon

the standard and are retained at any de- sired point of adjustment nearer to or farther from its lower end, according to the length of the brace member 14. The lower end of the brace member is secured to the 60 upper rear corner of the anchor by the bolt or rivet 15, which is inserted through holes provided therefor in said brace member and anchor, and the upper end is secured to the standard 1 by the bolt 3. To more securely 65 retain the anchor in place, I preferably pro- vide the upper and lower ends of the rec- tangular plate 6 upon the respective sides of said standard, with diagonal slits 16, 16, when the severed portions of said plate form 70 lugs 18, which are bent over and against the opposing convex surface of said standard, as shown in Fig. 2, when they coöperate with the opposing flanges 10 and 11 in retaining 75 said anchor in place upon the standard. The lower ends of the standard 1 are pref- erably flattened, as shown in Figs. 1 and 2, whereby they are caused to more readily puncture the earth as the standard is being driven. The apertures 2 are preferably 80 made slightly elongated to facilitate enter- ing the bolt 3.

The brace member 14 is preferably formed of channel iron, whereby the maximum strength of the material is attained at the 85 minimum weight of material.

Having thus described my invention, what I claim as new, and desire to secure by Letters Patent, is—

1. In a device of the described class, the 90 combination of a standard, U-shaped in cross section, an anchor comprising two vertically arranged plates, one edge of one of said plates being provided with a plurality of in- tegrally formed outwardly curved members 95 adapted to surround and closely fit two op- posite sides of the convex surface of said standard, and a brace secured at its upper end to said standard and at its lower end to 100 said anchor.

2. In a device of the described class, the 105 combination of a standard, U-shaped in cross section, an anchor comprising two vertically arranged plates, one edge of one of said plates being provided with a plurality of in- tegrally formed outwardly curved mem- bers adapted to surround and closely fit the 110 convex surface of said standard, and a brace secured at its upper end to said standard and at its lower end to said anchor, the other

plate comprising said anchor being provided with integrally formed lugs adapted to be bent over and partially around the convex surface of said standard upon the respective 5 sides opposite the standard-inclosing members of the first named plate, substantially as specified.

In testimony whereof I affix my signature in the presence of two witnesses.

EDWARD C. KAHN.
